TRAY MOVING APPARATUS

Merle E. Hanson, Chicago, Ill.

Application December 5, 1945, Serial No. 632,981

17 Claims. (Cl. 214—38)

1

This invention relates generally to candy manufacturing apparatus, and more particularly to improved apparatus adapted for use in the final steps of the manufacture of confections, such as the dipping of chocolates and other coated confections.

In the process of producing hand dipped chocolates and the like, it has been common for those engaged in the dipping operation to handle the trays upon which the dipped candies are placed for cooling. Such handling of the trays was done to keep them in a convenient position for the placement of the dipped candies and to put the trays upon racks for cooling and eventual packing.

My present invention has for a general object the provision of improved apparatus for use in dipping confections and the like which not only eliminates the necessity of the handling of trays of dipped confections by the operator, but also facilitates the speed and efficiency of the operation.

It is a further object of my present invention to provide apparatus for use in the dipping of confections and adapted to accommodate a rack for carrying a plurality of candy trays in spaced relationship and supported on wheels for manual movement, which apparatus effects sequential operations under the primary control of the operator to keep said operator supplied with empty trays from the rack, position the trays as they are filled and place the filled trays in successive spaced positions on the rack for cooling and movement.

As another object, my invention contemplates the provision of semi-automatic apparatus adapted to use in the manufacture of confections to keep an operator supplied with empty trays upon which to place the confections and to position those trays at the will of the operator for ease and convenience of filling, without necessitating the handling of the trays by the operator.

An additional object of this invention is to provide candy manufacturing apparatus adapted to be supplied with racks of empty trays and which substitutes filled trays for the empty ones as the operator fills successive trays and by a series of automatic operations initiated by the operator.

A further object of my invention is to provide

2

apparatus for shifting and handling trays used in the manufacture of dipped confections, which apparatus is power driven and has certain operations controlled by the operator and others which occur automatically in predetermined sequence.

Another object of the invention is to provide apparatus in accordance with one or more of the foregoing objects and in which the trays for a plurality of operators are moved under the control of each operator by power supplied from a common source.

Other objects and advantages of the invention will be apparent from the following description and the accompanying drawings in which similar characters of reference indicate similar parts throughout the several views.

Referring to the five sheets of drawings:

Fig. 1 is an end elevational and somewhat diagrammatic view of candy manufacturing apparatus embodying a preferred form of my present invention;

Fig. 2 is a fragmentary end elevational view of a part of the apparatus shown in Fig. 1;

Fig. 3 is a top plan view of the candy manufacturing apparatus depicted in Fig. 1 with certain parts removed to clarify the disclosure;

Fig. 4 is an enlarged fragmentary end elevational view of a portion of the apparatus shown in Fig. 1 with certain parts removed and others indicated more fully in dotted lines;

Fig. 5 is a perspective and somewhat diagrammatic view of one type of drive mechanism suited to the operation of my disclosed apparatus in its preferred form;

Fig. 6 is a fragmentary top plan view including a portion of the drive mechanism shown in Fig. 5 and certain additional details of structure;

Figs. 7, 8 and 9 are diagrammatic end elevational views of a portion of the apparatus shown in Fig. 1, which views show different operating positions of the parts and sequential steps in the operation of the apparatus; and

Fig. 10 is a fragmentary diagrammatic view of a portion of the apparatus shown in Figs. 7, 8 and 9, drawn to a slightly larger scale wherein the parts shown are depicted in a phase of operation which occurs somewhat prior to that illustrated in Fig. 8.

In general, my candy manufacturing apparatus

is adapted to facilitate the operation of hand dipping chocolates and other candies and confections and to minimize the manual handling of candy carrying trays by those engaged in the dipping operation.

Although the illustrative embodiment of my invention, which is depicted in the drawings, is suited to use in serving one or a plurality of dipping positions, I have shown its adaptation to two dipping positions for the purpose of the present disclosure. From this disclosure the omission of one position or the addition of others may be readily understood by those skilled in the art.

Referring generally to the layout and arrangement of the disclosed apparatus shown in Figs. 1, 3 and 4, a dipping table 20 has two operators' positions 22 and 23 on opposite sides thereof, as shown in Fig. 3. Substantially in the middle of the table 20 is a vat 24 equipped with suitable heaters and agitators (not shown) for maintaining a supply of chocolate or other dipping material in condition for use. Spouts 25 equipped with manually operable shut-off valves 26 are provided on opposite sides of the vat facing the operators' positions for draining the dipping material into dipping pans, such as 27 (Fig. 1), when and as desired.

Although other types of conveyors might be used in association with the apparatus for carrying a supply of clean, empty trays to the operator's position for filling with the dipped candies or confections and for removing the filled trays therefrom, I utilize racks 28 equipped with casters 29, which racks serve as trucks and storage containers during the cooling and between the dipping and packing operations. Each such rack desirably fits into a recessed end portion 30 of the table near the operator's position. In the dual installation disclosed, the recessed portions, into which the racks for each operator fit, are at opposite ends of the table.

As depicted in Figs. 1 and 2, the racks 28 may be of relatively simple construction. In the form shown, each rack has end frames 32 which are made of suitable material, such as angle iron strips, and include upright side strips 33 connected at their top and bottom ends by lateral ties 34. The end frames 32 are suitably secured together at their top and bottom ends by transverse strips similar to the lateral ties 34. At the bottom the framework is secured to and carried by a base 35, at the corners of which base the casters 29 are rotatably supported.

Intermediate the bottom and top ends of each side frame 32 a series of inwardly facing angle strips 36 provides supports for trays 37. The angle strips on each end frame 32 are vertically spaced and horizontally disposed in substantially parallel relationship. The ends of each angle strip 36 are secured to the upright side strips 33; the strips on the opposite side frames being in opposed relationship and disposed at common levels. The spacing between adjacent tray supporting strips is sufficient to provide space for pieces of candy or the like, such as 38 in Fig. 2, and to allow for the circulation of air between and around the pieces of candy. The ends of the tray supporting strips 36 being open and unobstructed between the end frames 32, trays may be slid into or out of the rack from either end.

In describing parts which are duplicated in different parts of the apparatus for the provision of the plurality of operators' positions, the same reference numerals will be used to identify the

similar parts and to avoid duplication in the description, it being understood that the function and operation of the apparatus for the two positions are alike.

At each operator's position, a lift 39 is provided in the recessed end portion 30 of the table for moving the rack 28 during the supply and removal of trays to and from that position.

In my disclosed embodiment of the invention, 10 each lift 39 has vertically disposed side rails 40 which are substantially parallel to one another and extend upwardly above the top of the table to a height dependent upon the height of the racks 28; the height of the side rails 40 being

15 sufficient that the lowermost tray carrying support of the rack may be lifted to substantially table height. The side rails 40 are supported by means, such as brackets 42, secured to the floor, and brackets 43 secured to the end of the table

20. Each side rail 40 has an inwardly facing channel 44 in which parallel side strips 45 of a lift frame 46 are supported for vertical sliding movement. The side strips of the lift frame 46 are secured together at spaced positions by cross strips, such as 47. Near the top the side rails 40 are braced by suitable cross and diagonal strips 48 and 49, respectively.

At the bottom the lift frame 46 has secured thereto outwardly projecting arms 50 which in 30 the lowered position of the lift normally project beneath the base 35 of the rack so that when a rack is rolled into its position in the recessed end portion 30 of the table, its base passes over the projecting arms. Thus, when the lift is raised, the arms 50 engage the base of the rack and carry the rack upwardly.

In order to provide retaining means for the lift having stop positions corresponding to the separation of the tray supports of the rack 28, 40 a ratchet mechanism, including a toothed strip 52 and a coacting spring urged pawl 53 (Figs. 3 and 4), is provided along one edge of the lift frame 46; that is, the toothed strip 52 is secured to the lift frame and has outwardly facing teeth 45 separated by amounts corresponding to the spacing between the tray carrying support strips 36 of the rack 28. The pawl 53 is slidably carried by one of the side rails 40 and is normally biased into engagement with the teeth 54 by means such as a spring 55.

It is desirable to provide means, such as a conventional dash-pot, a brake, or a counterbalance, to limit the rate of downward movement of the lift when the pawl 53 is released. In the present 55 instance I have indicated the use of counterweight (not shown) which acts through a cable 56 having one end attached to the lift frame 46. The cable 56 extends upwardly from the lift frame and over suitable pulleys (not shown) to a counterweight having the mass necessary substantially to balance the weight of the lift frame and rack.

For operating the pawl 53 to effect its release 65 from the teeth 54, a manually operable lever 57 has one end rotatably connected to a bracket 58 on the table 20 and its other end extends upwardly to a position above the top of the table, as shown in Fig. 4. A rod 59 secured to and extending from the pawl 53 is connected to the lever 57 so that when the lever is moved to a position such as that indicated in dot and dash lines at 57a in Fig. 4, the pawl 53 is withdrawn from the teeth 54 to release the ratchet holding mechanism, thereby permitting the lift and rack 70 to be lowered.

In the preferred manner of operation of the disclosed apparatus, each rack 28 is of a height comparable to that of the top of the table 20 and, when initially placed in position on the lift 39, has all but the uppermost of the tray carrying supports filled with empty trays. Starting with the rack in the lowered position of the lift, the uppermost tray carrying support is thus ready to receive a filled tray and the rack carries replacement trays for each of the succeeding positions.

At each position of elevation of the rack 28 determined by the teeth 54 of the ratchet mechanism, an empty tray is supplied to the operator and a filled tray is placed upon a tray support of the rack. To facilitate speed and convenience of filling the trays which promote efficiency of action, I have provided means under the manual control of the operator for moving the trays relative to the operator's position to effect convenience in the placement of pieces of candy by the operator during the filling of the trays.

To limit fatigue of the operator, to prevent manual handling of the trays by the operator, and to promote efficiency, the mechanism by which the trays are moved past the operator's position is manually controlled, and the supplementary tray supplying and tray removing operations are automatic, sequential and subordinate to the movement of the trays as they are filled.

Various types of drive mechanisms might be utilized for effecting the desired operation and control, but in the present instance a power driven mechanism is utilized which is driven by a motor or prime mover 60 which desirably has as a correlative part a speed reducing mechanism 62. Having reference to Figs. 3, 5 and 6, my illustrative drive mechanism, through which the parts of the apparatus are power-driven, includes a continuously operating shaft 63 driven from an output shaft 64 of the speed reducing mechanism 62 through suitable means, such as a chain 65 which coacts with sprockets 66 and 67 secured to shafts 63 and 64, respectively.

Meshing beveled gears 68 and 69, one secured to the mid-portion of the shaft 63 and the other secured to the end of a second continuously operating shaft 70, serve to drive the shaft 70. The position of the shaft 70 is desirably such that it extends upwardly through the table 20 and into the vat 24 to drive the agitators in that vat.

A beveled gear 72 is mounted at each end of the shaft 63, through which the manually controlled parts at each of the operators' positions are actuated. In each instance the beveled gear 72 meshes with a second beveled gear 73 which is secured to one end of a shaft 74. At the other end of the shaft 74 is mounted one friction element 75 of a normally disengaged friction clutch 76. A shaft 77, which is axially aligned with the shaft 74, carries the other friction element 78 of the clutch 76.

The normally disengaged friction elements 75 and 78 of the clutch are biased toward engagement by a spring 79 which has one end abutting a fixed collar 80 on the shaft 77 and its other end abutting the end surface of the clutch element 78. Preferably, the clutch element 75 is fixedly secured to the shaft 74 and the clutch element 78 is drivingly connected to the shaft 77 through a splined joint which permits axial movement of the element 78 relative to the shaft 77 to and from engagement with the element 75. A yoke 82, having integrally formed and an-

gularly disposed arms 83 and 84 which form a bell crank on one side thereof, is supported for rocking movement by fixed support means such as brackets 85. At their ends the legs of the yoke 82 are pivotally connected to the friction element 78 of the clutch. The extending end of the arm 84 of the bell crank is pivotally connected to a clutch actuating rod 86. Biasing means, such as a spring 87, having one end connected to the actuating rod 86 and its other end anchored, exerts a force through the bell crank and yoke 82 upon the friction element 78 of the clutch which is sufficiently strong to overcome the normal biasing force of the spring 79, thus normally holding the clutch in its disengaged position.

As illustrated in Figs. 3 and 4, the clutch actuating rod 86 has its end opposite the yoke 82 connected to a lever arm 88 of a manually operable foot pedal 89, the manually operable portion of which is easily accessible at the operator's position. The end of the lever 88 opposite the foot pedal 89 is rotatably secured to a fixed anchor bracket 90. The spring 87 normally holds the foot pedal 89 in a raised position so that downward movement thereof by the operator effects engagement of the friction elements 75 and 78 of the clutch 76 to drive the shaft 77 and a sprocket 92 which is secured to that shaft.

The shaft 70 has drivingly secured thereto a gear 93, on opposite sides of which are meshing gears 94 through which automatically and sequentially operated parts of the apparatus are driven at each of the operators' positions. For effecting the operation of those parts at each position, each gear 94 is secured to a shaft 95, which shaft also has mounted thereon one friction element 96 of a self-releasing clutch 97. A second friction element 98 of the self-releasing clutch 97 is coaxially mounted upon an aligned shaft 99. The friction element 98 is connected to the shaft 99 through means such as a splined joint which permits axial movement of that element relative to the shaft. The friction element 98 of the clutch is normally biased toward engagement with the friction element 96 to effect a driving connection between the shafts 95 and 99. However, the friction element 98 of the clutch 97 is normally held in a position in which the clutch is disengaged by a trigger type release mechanism 100 which, when released, permits one revolution of the clutch with the friction elements drivingly engaged and then automatically effects their disengagement.

As depicted in Fig. 6, the trigger type release mechanism 100 includes a bell crank type operating arm 101, the mid-portion of which is pivotally supported at 102. The end of the actuating arm 101 remote from the clutch 97 is connected to one end of an actuating cable 103 and also to one end of a biasing spring 104, the other end of which is anchored. The other end of the operating arm 101 has secured thereto a projecting pawl 105 adapted releasably to engage a camming surface 106 of a catch 107. The spring 104 biases the arm 101 toward the position of engagement of the pawl and camming surface. A stop 108 limits the movement of the arm in the direction toward which it is biased by the spring 104.

Force applied to the actuating cable 103 in the direction indicated by the arrows in Fig. 6 overcomes the biasing force of the spring 104 and moves the operating arm 101 to a position in which the pawl 105 is disengaged from the cam-

ming surface 106 of the catch 107. Such release of the catch from the pawl releases the friction element 98 of the clutch for movement axially of the shaft 99 as the result of biasing force against that friction element whereupon the friction elements of the clutch are drivingly engaged. As soon as the friction elements of the clutch 97 are engaged, the friction element 98 and shaft 99 are driven through the shaft 95 and friction element 96. Hence, although the operating arm 101 is released by the release of the force supplied through the cable 103, very soon after the disengagement of the pawl 105 from the gauge 107, the gauge will have moved away from the pawl and the operating arm will merely return to its normal position against the stop 108 until the friction element 98 of the clutch has been driven substantially one revolution. Being returned to its normal catch-engaging position, the pawl 105 will reengage the camming surface 106 at the end of the revolution of the friction element 98 to again effect disengagement of the elements of the clutch 97. It may thus be understood that the clutch 97 is self-releasing and will turn the shaft 99 through one revolution each time the trigger type release mechanism is actuated for an interval of time and then released.

The shaft 99 has mounted thereon a gear 109 which meshes with a gear 110 on a shaft 112 to drive the shaft 112 each time the shaft 99 is driven through the clutch 97. Desirably, there is a one to one ratio between the gears 109 and 110 so that each revolution of the shaft 99 turns the shaft 112 through one revolution. At the upper end of the shaft 112 is a lift operating cam 113 having a cam surface 114 of a length such that it functions during only approximately one-half of each revolution of the shaft 112.

Shafts 115 and 116 are driven from the shaft 112 through coacting pairs of beveled gears 117, 118, 119 and 120 secured to the respective shafts. The shaft 116 has mounted thereon a sprocket 122 which is driven during each period of operation of the shaft 112.

Having thus described the mechanism by which the various parts of the apparatus are driven, the description will proceed with the application of the driving mechanism to the associated apparatus to secure the desired results. One of the desired functions of the apparatus is to move a tray relative to the operator's position in a manner such that as the tray is filled with pieces of candy by the operator, the filled portion is moved away and the empty portion of the tray is kept within easy reach and at a position handy to the operator for placement of the pieces of candy. In the disclosed apparatus the movement of the tray in such a manner past the operator's position also moves it toward and onto one of the tray carrying supports of the rack.

At one side of the operator's position and aligned with an open end of the tray carrying supports of the rack 28 is a tray support 123 adapted to carry a plurality of the trays 37 in stacked relationship one upon the other. The height of the stack of trays carried by the support 123 is related to the spacing between the adjacent tray carrying supports 36 of the rack. That is, the major portion of the base 124 of the tray support 123 is substantially aligned or slightly above the top of the tray carried by one tray carrying support of the rack; while the bottom of the top tray of the stack carried by the support 123 is substantially aligned with or slightly above the next higher tray carrying sup-

port of the rack. With this alignment of the trays of the stack, the uppermost tray of the stack on the support 123 may be moved linearly relative to the next lower tray and into an empty tray carrying support of the rack.

In order to keep the trays of the stack aligned on the support 123 and to guide the uppermost tray of that stack as it is moved relative to the operator and into the rack, the support is provided with sides 125 and 126 which extend upwardly from the base 124 to a height at least sufficient to engage a portion of the opposite side edges of the uppermost tray. An end wall 127 of substantially the same height as the sides 125 and 126 is provided on the end of the support 123 remote from the rack 28.

At the end of the support 123 adjacent the rack 28 the base 124 has a portion 128 sloping downwardly toward the rack. The downwardly sloping portion 128 is of sufficient length to serve as a guide for the endwise movement of trays into the support beneath the upper trays of the stack. However, its length is desirably less than half the total length of the support so that the stack of trays normally rests on the horizontally disposed portion of the base.

Extending across the end of the support 123 adjacent the rack position and secured to the support is a strip 129 which serves as a stop to prevent endwise movement of the trays below the uppermost one of the stack as that uppermost one is moved from the stack to the rack. The top surface of the strip 129 is, therefore, slightly below or flush with the lower surface of the uppermost tray of a normal stack of trays. The lower surface of the strip 129 is above the end of the sloping portion 128 an amount sufficient to permit the passage of the end of a tray into the support below the other trays in the support and between that lower surface and the end of the sloping portion. Thus, empty trays may be pushed into the support below the stack, and upon each such insertion of an empty tray the upper trays of the stack move upwardly in the support between the sides and ends thereof.

Movement of the trays past the operator's position as they are filled and onto the rack 28 without handling of the trays by the operator is effected by a mechanism driven from the sprocket 92 and illustrated in Fig. 4. As has been previously explained, the sprocket 92 is driven from the power driven mechanism and its movements are controlled by the operation of the foot pedal 89 (Fig. 3).

Referring to Fig. 4, the sprocket 92 is drivingly connected to a second sprocket 130 by suitable flexible driving means such as a chain 132. The sprocket 130 is rotatably supported by a shaft 133 and has secured to one surface thereof a toothed ratchet 134 which coacts with a pawl 135 to prevent reverse rotation of the sprocket 130. Resilient means, such as a spring 136, biases the pawl 135 into engagement with the teeth of the ratchet 134. A cam 137 is secured to the shaft 133 to be driven by the rotation of the sprocket 130.

A tray moving arm 138 has its lower end supported for swinging movement by a shaft 139 at a position below the axis of rotation of the cam 137. The arm 138 extends upwardly from its supported end to a position adjacent one side of the tray support 123 and has a slot 140 in its upper end which drivingly engages a pin 142 projecting outwardly from the outer side of a tray 75 moving slide 143. Resilient means, such as a

spring 144, has one end connected to an intermediate portion of the arm and has its other end anchored so as normally to bias the arm 138 to a position such that a tray engaging edge 145 of the slide 143 is normally out of the way of a tray moving upwardly in the support 123 and in position for engagement with the end surface of a tray.

A guide rail 146 secured to and extending longitudinally along one side of the tray support 123 slidably carries the slide 143 for movement along the edge of that support. As shown in Fig. 3, the tray engaging edge 145 of the slide 143 is offset from the guide rail 146 to a lateral position such that it engages one side of the end surface of the uppermost tray of the stack. Thus, upon movement of the slide 143 longitudinally of the support, the uppermost tray is pushed along on that support and finally moved into a tray support of the rack 28.

In order to effect the movement of the slide 143 as a result of operation of the foot pedal 89, the arm 138 has rotatably supported on one side thereof and in alignment for engagement with the cam 137 a cam follower 147. As depicted in Figs. 4 and 7, the rotational movement of the cam 137 moves the cam follower 147 and swings the arm 138 to positions determined by the position of the cam 137. Reverse movement of the cam during the forward progress of the arm 138 to move a tray from the support 123 to the rack 28 is prevented by the action of the ratchet 134 and its coacting pawl 135. The intermediate and extreme positions of forward movement of the arm 138 are illustrated in dot and dash lines in Fig. 4 at 138a and 138b. Fig. 7 also illustrates an intermediate position of forward movement of the arm 138 and slide 143.

Near the extreme limit of the forward movement of the arm 138, as indicated in Fig. 4, the intermediate portion of the arm engages a rotatably supported bell crank 148 which is carried by a suitable bracket 149. The end of the cable 103 is connected to the other arm of the bell crank 148 so that the resulting actuation of the bell crank by the arm 138 pulls the actuating cable 103 thereby to actuate the trigger release mechanism of the clutch 97.

Immediately upon engagement of the friction elements of the clutch 97, the sprocket 122 is driven from the driving mechanism to actuate a second tray moving mechanism for the purpose of moving an empty tray from the rack 28 to the bottom of the stack of trays in the support 123 so that the supply of trays in the stack is replenished each time one tray is filled and removed therefrom. Considered generally, the mechanism for moving empty trays from the rack 28 into the support 123 is quite similar to that used for moving the trays from the stack onto the rack. However, it is to be understood that the control of the movement of the trays from the stack to the rack is manual while after initiation, the control of the mechanism for moving the trays from the rack to the support is automatic in that the self-releasing clutch 97 remains engaged for a period of time sufficient for one cycle of operation of the latter mechanism.

Referring to Fig. 4, the sprocket 122 is drivingly connected to a sprocket 150 by flexible driving means, such as a chain 152. The sprocket 150 is rotatably supported by shaft 153, to which are secured a cam 154 and a toothed ratchet 155. A pawl 156 resiliently biased into engagement with the teeth of the ratchet 155 by a spring 157

prevents reverse rotation of the cam 154. One end of an arm 158 is supported for swinging movement by a shaft 159. The other end of that arm has a slot 160 therein which drivingly engages a pin 162 projecting from the outer side of a slide 163. A push rod 164 has one end carried by the slide 163 and its other end supported for longitudinal movement by the guide rollers 165 (Figs. 3 and 4). The slide 163 is supported by a guide rail 166 so that swinging movement of the arm 158 toward the rack position moves a tray engaging end 167 of the push rod 164 from a position adjacent a tray carrying support of the rack into and through the rack to move a tray into the support 123 in the manner depicted in Figs. 8 and 10.

Resilient means, such as a spring 168, having one end connected to the mid-portion of the arm 158 and its other end anchored, biases the arm 158 to a position such that the push rod 164 is withdrawn from the rack. A cam follower 169, carried by the mid-portion of the arm 158, engages the cam 154 so that the rotation of the cam 154 effects movement of the arm to intermediate and extreme positions such as those indicated in dot and dash lines at 158a and 158b in Fig. 4.

The design of the cam 154 is such that, although a full revolution of the cam is necessary for a full cycle of operation and its return to the starting position for another cycle, it is effective for producing full forward movement of the push rod and slightly less than one-half of a full revolution. The commencement of the forward movement of the push rod 164 coincides with the driving engagement effected by the clutch 97. Although the clutch 97 remains engaged for a period of time sufficient to complete a full revolution of the cam 154, the forward movement of the push rod is accomplished in slightly less than half of that time, after which the push rod is quickly withdrawn by the biasing force of the spring 168.

During the remaining period of time in which the clutch 97 is engaged, the shaft 112 (Figs. 3 and 5) continues to rotate to drive the lift operating cam 113. Like the push rod actuating cam 154, the lift operating cam 113 is effective during only substantially half of the period of operation of the clutch 97 and the work performing periods of operation of those two cams are thus separated.

As illustrated in Figs. 3 and 4, the lift frame 46 has secured thereto a vertically disposed rail 170, to which is secured a series of vertically spaced cam followers 172. The cam followers 172 project from the rail 170 to a position in which they are adapted to be engaged by the camming surface 114 of the lift operating cam 113. The spacing between the adjacent cam followers 172 corresponds to the spacing between the tray carrying supports 36 to the rack 28. During each cycle of rotation of the lift operating cam 113, the camming surface 114 of that cam engages one of the cam followers 172 to raise the lift one step; the lift being held in position at each step by the toothed strip 52 and its coacting pawl 53.

Reviewing the order and sequence of operation with reference to Figs. 7 to 10, inclusive, and to the description of the various parts of the apparatus, it may be readily understood that upon each intermittent operation of the foot pedal 89 by the operator, the top tray of the stack in the support 123 is moved past or from the operator's position a desired amount and onto a tray support of the rack 28. The movement of the upper-

most tray of the stack as it is filled is thus under the control of the operator and corresponds, for convenience, to the rate of filling the tray.

After each filled tray is moved onto a tray support of the rack, the arm 138 and tray moving slide 143 move quickly back to the starting position under the influence of the force of the spring 144; the arm 138 being released for return by the cam 137 after forward movement to that extreme forward position.

Upon reaching the extreme forward position, the arm 138 of the tray moving mechanism effects operation of the self-releasing clutch 97 to initiate the automatic operation by which an empty tray is moved into the stack to replace the one which has been filled and the movement of the lift together with the rack 28 to the next higher position. Since the operation of the tray moving mechanism, which moves an empty tray from the rack to the stack, is initiated by a completion of the movement of a filled tray into the rack, the movement of the empty tray into the stack will succeed in each instance the movement of a filled tray from the stack. The movements of the tray moving mechanism, which moves a tray from the rack, and the raising of the lift are automatically separated by the design and correlation of the cams 154 and 113. At the end of the automatic cycle of operation of the tray moving mechanism and the lift raising mechanism, the clutch 97 automatically releases, whereupon repeated operation results from the initiation of a new cycle.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In candy manufacturing apparatus adapted to be used in association with a portable rack provided with supporting casters upon which it may be moved to and from the apparatus and normally carrying a supply of trays in a plurality of tray carrying supports equidistantly spaced apart vertically, the combination comprising a lift having thereon means for carrying the rack vertically, means at one side of the lift supporting a plurality of empty trays one on top of the other with the uppermost one at a level corresponding to the top tray carrying support of the rack, manually controlled means for moving said uppermost one of the trays onto the adjacent tray carrying support of the rack in steps of selected lengths, means operable after the movement of said uppermost one of the trays onto the rack for moving an empty tray from a lower support of the rack to the bottom of said plurality of empty trays, ratchet means on said lift having steps corresponding in separation to the spacing of the tray carrying supports of the rack, means operable after the movement of an empty tray from the rack for moving the lift upwardly one step to align an empty support of the rack with the uppermost of said plurality of empty trays, power driven means for actuating said means for moving an empty tray from the rack and for moving said lift upwardly from one step of the rack to the next, and means for releasing the ratchet to lower the rack.

2. In candy manufacturing apparatus adapted to be used in association with a portable rack

provided with supporting casters upon which it may be moved to and from the apparatus and normally carrying a supply of trays in a plurality of tray carrying supports equidistantly spaced apart vertically, the combination comprising a lift having thereon means for carrying the rack vertically, means at one side of the lift and at a level corresponding to a tray carrying support of the rack for supporting a plurality of empty trays one on top of the other with the uppermost one at a level corresponding to the top tray carrying support of the rack, manually controlled means for moving said uppermost one of the trays onto the adjacent tray carrying support of the rack in steps of selected lengths, means operable after the movement of said uppermost one of the trays onto the rack for moving an empty tray from a lower support of the rack to the bottom of said plurality of empty trays, means operable after the movement of an empty tray from the rack for moving the lift upwardly a distance such that an empty tray carrying support of the rack is aligned with the uppermost of said plurality of empty trays, and means for actuating said means for moving an empty tray from the rack and for moving said lift upwardly.

3. In candy manufacturing apparatus adapted to be used in association with a portable rack provided with supporting casters upon which it may be moved to and from the apparatus and having a plurality of spaced tray carrying supports, the combination comprising a lift having thereon means for carrying the rack vertically, means at one side of the lift for supporting a stack of empty trays, one on top of the other, with the uppermost one of the trays at a level corresponding to a predetermined tray carrying support of the rack, means for moving the uppermost one of the trays toward and onto the adjacent tray carrying support of the rack in steps, means operable after the movement of said uppermost tray onto the rack for moving the rack a distance equal to the spacing between tray carrying supports, thereby to align another tray carrying support with another tray on the stack.

4. In candy manufacturing apparatus, the combination comprising rack means having a plurality of tray carrying supports, a supply of empty trays carried on all but one of said tray carrying supports, means adjacent one side of the rack for supporting an auxiliary stack of empty trays, one on top of the other, with the uppermost tray in a position to be filled and at a level such that its lower surface is substantially even with said one of the tray carrying supports, manually controlled means for moving said uppermost one of the trays from the auxiliary stack toward and onto said one tray carrying support in steps of selected lengths, means operable after the movement of said uppermost one of the trays onto said one tray carrying support for moving the next adjacent empty tray from said rack into the auxiliary stack, means operable after movement of an empty tray from the rack into the stack for moving the rack to a position in which the next empty tray carrying support thereof is aligned with the uppermost tray of the stack, and power operated means for moving the rack to successive positions.

5. In candy manufacturing apparatus, the combination comprising rack means having a plurality of spaced tray carrying supports, means ad-

jacent one side of the rack for supporting a stack of empty trays, one on top of the other, with the uppermost tray in a position to be filled and at a level for sliding movement into one of said tray carrying supports, manually controlled means for moving said uppermost one of the trays from the stack toward and onto said one of the tray carrying supports in steps of selected lengths, means operable after the movement of said uppermost one of the trays onto the rack for raising said stack a distance equal to the thickness of a tray, and means for moving the rack to a position for receiving the next succeeding tray from the stack on the next succeeding tray carrying support thereof in like manner.

6. In candy manufacturing apparatus, the combination comprising a work table with operators' positions on opposite sides thereof, main power driven means beneath the table and between the operators' positions, means at one side of each operator's position including a support having a portion adjacent one side of the table for carrying thereon a stack of empty trays with the uppermost tray of the stack substantially flush with the top of the table, a rack adjacent said one side of the table and at the end of said support remote from the operator's position, said rack having a series of vertically separated tray supports, the top one of which is normally aligned with said uppermost tray of the stack, a tray moving mechanism adapted intermittently to be actuated by said main power driven means to move the uppermost one of the trays from said stack onto the aligned tray support of said rack, foot operated control means for effecting actuation of the tray moving mechanism by the power driven means, a lift intermittently driven upwardly by the main power driven means for raising the rack in steps of a length determined by the separation between tray supports, means actuated by the tray moving mechanism at each full movement thereof for effecting upward movement of the lift one step by the main power driven means, and means intermittently driven by the main power driven means for supplying an additional tray to the stack each time one is removed therefrom.

7. In candy manufacturing apparatus, the combination comprising a work table with an operator's position at one side thereof, power driven means beneath the table, means at one side of the operator's position including a support having a portion adjacent one end of the table, said support carrying thereon a stack of empty trays with the uppermost tray of the stack at approximately table height, the edges of said uppermost tray remote from the operator's position normally being within easy reach of an operator for placing candy on the tray, a tray moving mechanism having a part engaging said uppermost tray of the stack for effecting progressive movement of the tray in a direction such that the surface of the tray passes progressively within easy reach of the operator, normally disconnected driving means for providing an actuating connection between the tray moving mechanism and the power driven means, foot pedal operated means at the operator's position for controlling the connection between the tray moving mechanism and the power driven means, whereby the operator may effect movement of said uppermost tray as desired, means onto which said uppermost tray is moved from the support by the tray moving mechanism, and means for raising said stack of trays each time one is removed.

8. In candy manufacturing apparatus, the com-

bination comprising a work table with an operator's position at one side thereof, power driven means, a tray for receiving pieces of candy placed thereon by the operator, means at one side of the operator's position supporting said tray for movement relative to the operator's position from a normal position in which the remote sides of the tray are within easy reach of the operator, a tray moving mechanism having a part engaging the tray for effecting said movement thereof, normally disconnected driving means for providing an actuating connection between the tray moving mechanism and the power driven means, manually operable means at the operator's position for controlling the connection between the tray moving mechanism and the power driven means, whereby the operator may effect said movement of the tray as desired, a rack having a series of tray carrying supports, said rack being disposed in a position such that the said tray is moved onto one of said tray carrying supports by the tray moving mechanism, and means driven by said power driven means for moving the rack to a position such that a succeeding one of said series of tray carrying supports is aligned to receive a tray from the tray supporting means.

9. In candy manufacturing apparatus in which trays are utilized to carry pieces of candy and said trays are successively moved past an operator's position while being filled with candy and onto separated tray supports of a rack for cooling the candy, the combination comprising, a tray moving mechanism including a part adapted drivingly to engage the ends of successive trays at a starting position, the limits of movement of said tray moving mechanism being such as to move a tray from said starting position onto said rack, power driven means, means including a clutch mechanism for actuating the tray moving mechanism from the power driven means to move a tray from the starting position toward and onto the rack, manually operable control means for operating said clutch to move the tray as desired, means biasing the tray engaging part of the tray moving mechanism to the starting position, means included in said tray moving mechanism for releasing the tray engaging part at the end of its movement toward the rack for return to the starting position by said biasing means, means for preventing movement of the tray engaging part toward the starting position after being moved therefrom and before release by said means, a lift for said rack, means including a self-disengaging clutch mechanism for intermittently actuating the lift from said power driven means, and means actuated by said tray engaging part at the end of its movement toward the rack for initiating operation of said self-disengaging clutch.

10. In candy manufacturing apparatus in which trays are utilized to carry pieces of candy and said trays are successively moved past an operator's position while being filled with candy and onto separated tray supports of a rack for cooling the candy, the combination comprising a tray moving mechanism including a part adapted drivingly to engage the ends of successive trays at a starting position, the limits of movement of said tray moving mechanism being such as to move a tray from said starting position onto said rack, power driven means, means including a clutch mechanism for actuating the tray moving mechanism from the power driven means to move a tray from the starting position toward and onto the rack, manually operable control means for

operating said clutch to move the tray as desired, means biasing the tray engaging part of the tray moving mechanism to the starting position, a cam having driving and quick return portions included in said tray moving mechanism for effecting movement of the tray engaging part and quick release thereof at the end of its movement toward the rack for return to the starting position by said biasing a ratchet mechanism, and for preventing movement of the tray engaging part toward the starting position after being moved therefrom and before release by said means.

11. In candy manufacturing apparatus in which trays are utilized to carry pieces of candy and said trays are successively moved past an operator's position while being filled with candy and onto separated tray supports of a rack for cooling the candy, the combination comprising a tray moving mechanism including a part adapted drivingly to engage successive trays at a starting position, said tray moving mechanism having limits of forward and reverse movement such that said part reciprocates between starting and release positions, power driven means, normally released coupling means for actuating the tray moving mechanism from the power driven means to effect forward movement of said part, manually operable control means for operating said coupling means to effect forward movement of said part in desired increments, said coupling means including a cam and a ratchet mechanism for effecting the forward movements of said part and preventing reverse movement of said part between forward movements thereof until said release position is reached, and means including a cut-away portion of said cam for effecting quick return of said part from the release position to the starting position.

12. In candy manufacturing apparatus in which trays are utilized to carry pieces of candy and said trays are conveyed by racks to and from a position at which the trays are filled with candy, the combination comprising a rack having spaced tray supports and origin—all being loaded with empty trays carried by all but one of said tray supports, means for successively moving trays onto said rack starting with said one of the tray supports, means for successively moving said empty trays from the tray support of the rack adjacent the previously filled tray, and means for moving said rack to successive positions for insertion of filled trays and removal of empty trays, the last mentioned means including a lift and power driven means for actuating the lift, said lift embodying means having spaced steps for holding it in successive raised positions, and said power driven means incorporating an intermittently operated element for moving the lift between said successive positions.

13. In candy manufacturing apparatus wherein in a rack having spaced tray supports is moved vertically in steps past a predetermined position, the combination comprising a lift having side members movable between guides, means for moving the lift in successive steps, rack and pawl means for retaining the lift in position between said successive steps, manually controlled means for moving a tray into said rack at each of said successive steps of the rack, and said means for moving the lift including a cam and a coacting cam follower, power driven means for moving the cam, a self-releasing clutch for drivingly connecting the cam to the power driven means for a period sufficient to raise the lift

one step, and means actuated by said manually controlled means for initiating operation of said self-releasing clutch.

14. In candy manufacturing apparatus wherein in a rack initially carrying a supply of empty trays in spaced tray carrying supports is utilized to supply empty trays at a filling position and remove filled trays from said filling position, the combination comprising power driven means, 5 rack carrying means, means including a self-releasing clutch for intermittently connecting the rack carrying means to the power driven means to move the rack in steps dependent upon the spacing between said tray carrying supports, manually controlled means for moving filled trays onto said tray carrying supports at successive positions of the rack, means for moving an empty tray from said rack at each of the successive positions of the rack, the last mentioned means being actuated from the power driven means through the self-releasing clutch, means for sequentially timing the movements of the rack carrying means relative to the operations of the means for moving empty trays from the rack, and 10 means responsive to operations of said manually controlled means for initiating successive operations of said self-releasing clutch.

15. In candy manufacturing apparatus wherein in a rack initially carrying a supply of empty trays in spaced tray carrying supports is utilized to supply empty trays at a filling position and remove filled trays from said filling position, the combination comprising power driven means, rack carrying means, means including a self-releasing clutch for intermittently connecting the rack carrying means to the power driven means to move the rack in steps dependent upon the spacing between said tray carrying supports, manually controlled means for moving filled trays onto said tray carrying supports at successive positions of the rack, means for moving an empty tray from said rack at each of the successive positions of the rack, the last mentioned means being actuated from the power driven means through the self-releasing clutch, and means for sequentially timing the movements of the rack carrying means relative to the operations of the means for moving empty trays from the rack.

16. In candy manufacturing apparatus, wherein empty trays are supplied from a movable rack having spaced tray carrying supports, the combination comprising power driven means including a self-releasing clutch and a cam for moving the rack in steps dependent upon the spacing of the tray carrying supports, means also driven by said power driven means through the self-releasing clutch and including another cam for moving a tray from the rack at each of said successive steps, and said cams being timed to 55 separate the operations of the rack moving means and tray moving means during each cycle of operations of the self-releasing clutch.

17. In candy manufacturing apparatus wherein trays are utilized to carry quantities of candy and said trays are used from a stack, the combination comprising a support for said stack including a base, side and end walls, said side walls extending upwardly from the base a distance such that they at least partially overlap the side surfaces of the uppermost tray of the stack, a portion of said base sloping downwardly away from the stack at one end and to an extent such that the normal space between the base and the lowermost tray of the stack at said one end 65 is greater than the thickness of a tray, said end

wall at said one end of the base being spaced upwardly from the base more than the thickness of a tray to permit trays to be slipped into the support at the bottom of the stack, and the height of said end wall at said one end of the base being lower than the top of the stack by an amount such that the uppermost tray of the stack may be slipped from the stack over said end wall and between the side walls.

Certificate of Correction

Patent No. 2,459,524.

January 18, 1949.

MERLE E. HANSON

It is hereby certified that errors appear in the printed specification of the above numbered patent requiring correction as follows:

Column 10, line 61, for the words "to the" read *of the*; column 15, line 9, claim 10, for "a ratchet mechanism, and" read *means, and a ratchet mechanism*; and that the said Letters Patent should be read with these corrections therein that the same may conform to the record of the case in the Patent Office.

Signed and sealed this 17th day of May, A. D. 1949.

[~~SEAL~~]

THOMAS F. MURPHY,
Assistant Commissioner of Patents.
